CLAIM

We claim ornamental design for a height-adjustable desk, as shown and described.

DESCRIPTION

FIG. 1 is a top perspective view of a height-adjustable desk; FIG. 2 is a top plan view thereof; FIG. 3 is a bottom plan view thereof; FIG. 4 is a front elevation view thereof; FIG. 5 is a rear elevation view thereof; FIG. 6 is a left side elevation view thereof; FIG. 7 is a right side elevation view thereof; and, FIG. 8 is a top perspective view thereof with the desktop raised.

The broken line portion of the figure drawings is included to show features that form no part of the claimed design.

1 Claim, 5 Drawing Sheets(56)
